ABSTRACT

In an audio amplifier comprising first and second transistors with their emitter-collector circuits connected in series to provide an output terminal, first and second sources respectively connected in series with the first and second transistors and a loudspeaker connected directly to the output terminal, there is provided a protective device for the loudspeaker comprising a circuit interrupting element connected between the output terminal and the loudspeaker and a control circuit responsive to a DC voltage exceeding a predetermined level which appears at the output terminal for operating the circuit interrupting element.

SHEET 3 OF 3

The diagram illustrates a circuit connection. On the left, a switch labeled "13a" is shown with two positions. The top position connects terminal 19 to ground. The bottom position connects terminal 19 to a central node. This central node is connected to a terminal block labeled "19". The terminal block has four pins: Pin 1 is connected to ground, Pin 2 is connected to a diode labeled "D8" (pointing to Pin 3), Pin 3 is connected to a diode labeled "D9" (pointing to Pin 4), and Pin 4 is connected to a diode labeled "D9'". The diodes D9 and D9' are connected in series with the central node. The diodes D8 and D9 are connected in parallel with the central node. The diodes D9 and D9' are connected in parallel with the central node. The diodes D8 and D9 are connected in parallel with the central node.

PROTECTIVE DEVICE FOR LOUDSPEAKER

BACKGROUND OF THE INVENTION

This invention relates to a loudspeaker protective device of an audio amplifier and more particularly to a device for protecting a loudspeaker which is connected directly to the output terminal of an amplifier without utilizing a coupling capacitor against damages caused by a high DC voltage appearing at the output terminal.

A recent trend in the art is to use an audio amplifier wherein a loudspeaker is connected directly, or without using a coupling capacitor, to an output terminal between serially connected emitter-collector circuits of two output transistors for the purpose of improving the low frequency characteristic. A plurality of such amplifiers are used for multi-channel circuits. When such an amplifier becomes out of order, a relatively high DC voltage of the positive or negative polarity often appears at the output terminal of the amplifier, and such excessively high DC voltage not only damages the loudspeaker but also degrades the sound quality. It is therefore highly desirable to detect such an abnormal condition and to disconnect the loudspeaker from the circuit. Especially, in amplifiers for use in multi-channel circuits, it is desirable to provide a relatively simple protective device or circuit which can protect all loudspeakers of respective amplifiers. However, it has not yet been proposed such a protective device, especially suitable for use in multi-channel circuits.

SUMMARY OF THE INVENTION

Accordingly, it is the principal object of this invention to provide a novel protective device responsive to an abnormal DC voltage appearing at the output terminal of an amplifier for disconnecting a loudspeaker from the amplifier.

Another object of this invention is to provide such a protective device which can be used in common for a plurality of amplifiers.

In accordance with this invention, for use in an audio amplifier comprising first and second transistors with their emitter-collector circuits connected in series to provide an output terminal, first and second sources respectively connected in series with the first and second transistors, and a loudspeaker connected directly to the output terminal, there is provided a protective device for the loudspeaker comprising a circuit interrupting element connected in series with a first closed circuit including the first transistor, the first source and the loudspeaker and with a second closed circuit including the second transistor, the second source and the loudspeaker, and a control circuit which operates when a positive direct current voltage appearing at the output terminal reaches a predetermined level for interrupting the circuit interrupting element.

The circuit interrupting element may take the form of a fusible element or a relay contact thus reducing the cost of the protective device. Where the invention is applied to multichannel amplifiers, the relay contacts inserted in the respective loudspeaker circuits may be operated by a single common relay.

Where a fusible element is used it is interrupted by passing a short circuit current therethrough by operating a short circuiting circuit in response to an abnormal DC voltage appearing at the output terminal of the amplifier. On the other hand where a relay contact is used

as the circuit interrupting element a rectifier is provided for converting the abnormal DC voltage appearing at the output terminal into a unidirectional output irrespective of the polarity of the abnormal voltage and a relay responsive to the unidirectional voltage is also provided for operating the relay contact.

The novel protective device can also be used to protect a plurality of loudspeakers associated with multi-channel amplifiers with the same control circuit but by adding only a small number of circuit elements.

BRIEF DESCRIPTION OF THE DRAWINGS

FIGS. 1 and 2 are connection diagrams of similar embodiments of this invention comprising a fuse connected in series with a loudspeaker circuit and a unidirectional short circuiting circuit;

FIGS. 3 and 4 are connection diagrams of modified embodiments of this invention comprising a relay contact connected in series with a loudspeaker circuit, a rectifier circuit and a relay circuit controlled by the output from the rectifier circuit;

FIG. 5 shows a connection diagram of another embodiment of this invention applied to multi-channel amplifiers; and

FIGS. 6 and 7 are connection diagrams of still further embodiments of the invention similar to that shown in FIG. 5 and adapted to protect loudspeakers associated with two channel amplifiers and three channel amplifiers respectively.

DESCRIPTION OF THE PREFERRED EMBODIMENTS

The audio amplifier 1a shown in FIG. 1 comprises a first NPN-type output transistor TR_1 , a second PNP-type output transistor TR_2 , with their collector-emitter circuits connected in series, a first source of supply E_1 with its positive pole connected to the collector electrode of the first transistor and the negative pole grounded, a second source of supply E_2 with its negative pole connected to the collector electrode of the second transistor and the positive pole grounded, an output terminal 2 connected to the juncture between the emitter electrodes of the first and second transistors, and a loudspeaker 3 connected directly between the output terminal 2 and the ground without utilizing a coupling capacitor as has been the common practice. One of the audio signal input terminals 4 is connected to the base electrodes of both output transistors via a coupling capacitor 5 whereas the output terminal is grounded. It is to be understood that the invention is not limited to the particular amplifier illustrated.

According to this invention fusible element 6 is connected between the output terminal 2 and the loudspeaker 3. Thus, there are provided two closed circuits, one including source E_1 , the first transistor TR_1 , fuse 6 and loudspeaker 3, the other including source E_2 , the second transistor TR_2 , fuse 6 and loudspeaker 3. One terminal of the loudspeaker 3 connected to output terminal 2 is grounded through a series circuit including a resistor R_1 and a capacitor C_1 which is connected in parallel with other series circuits, one including a diode D_1 and a silicon controlled rectifier SCR_1 and the other a diode D_2 and a silicon controlled rectifier SCR_2 which are poled as shown in the drawing. In parallel with sil-

icon controlled rectifier SCR_1 is connected a series circuit including an NPN-type transistor Q_1 , a resistor R_2 connected to the collector electrode of transistor Q_1 and a resistor R_3 connected to the emitter electrode of the transistor so as to impress the voltage drop across resistor R_3 between the gate and cathode electrodes of the silicon controlled rectifier SCR_1 . In the same manner, in parallel with silicon controlled rectifier SCR_2 is connected a second series circuit including a PNP transistor Q_2 , resistors R_4 and R_5 connected in series with the collector electrode of transistor Q_2 and a resistor R_6 connected to the emitter electrode of this transistor so as to apply the voltage drop across resistor R_4 between the gate and cathode electrodes of the silicon controlled rectifier SCR_2 . A capacitor C_2 and a resistor R_7 are connected between the base electrode of transistor Q_1 and the ground and a capacitor C_3 and a resistor R_8 are connected in parallel between the base electrode of transistor Q_2 and the ground. Diodes D_3 and D_4 poled as shown are connected respectively between the base electrodes of transistors Q_1 and Q_2 and the juncture between resistor R_1 and capacitor C_1 .

Assuming now that an abnormal DC voltage of positive polarity appears at the output terminal 2 owing to some reason, the DC voltage will be impressed upon the base electrode of transistor Q_1 via resistor R_1 and diode D_3 . When this abnormal voltage exceeds a predetermined value transistor Q_1 becomes conductive whereby the voltage drop across resistor R_3 caused by a current flowing through diode D_1 , resistor R_2 and transistor Q_1 is impressed upon the gate electrode of silicon controlled rectifier SCR_1 , thus, rendering the same conductive. This increases the current flowing from source E_1 through transistor TR_1 , fuse 6, diode D_1 , silicon controlled rectifier SCR_1 , to the ground, thus melting fuse 6 to interrupt the output circuit to the loudspeaker.

On the other hand, upon appearance of an abnormal voltage of negative polarity at the output terminal 2, this negative DC voltage is impressed upon the base electrode of transistor Q_2 through resistor R_1 and diode D_4 , thus turning ON transistor Q_2 . When this negative voltage exceeds a predetermined value, the voltage drop across resistor R_4 caused by the current flowing through diode D_2 and transistor Q_2 is impressed upon the gate electrode of silicon controlled rectifier SCR_2 , thus turning ON the same. Consequently, fuse 6 is melted by the current flowing from source E_2 through the ground, silicon controlled rectifier SCR_2 , diode D_2 , fuse 6 and transistor TR_2 .

In this manner, a unidirectional short circuiting circuit is always established irrespective of the polarity of the abnormal DC voltage appearing at output terminal 2, thus interrupting fuse 6 to provide positive protection for loudspeaker 3.

The above described protective device for the loudspeaker is advantageous in that it can not only protect the loudspeaker associated with a single amplifier, but it can also protect loudspeakers associated with a plurality of amplifiers by a simple modification. More particularly, where there is another loudspeaker 3 connected to another amplifier 1b having the same construction as amplifier 1a, by way of a fuse 6, the upper terminal of said another loudspeaker 3 is connected to the anode electrode of diode D_2 through a diode D_2'

and to the cathode electrode of diode D_1 through a diode D_1' of the opposite polarity as shown by dotted lines. The upper terminal of said another loudspeaker 3 is also connected to the juncture between resistor R_1 and capacitor C_1 via resistor R_1' . This simple modification protects loudspeaker 3 associated with amplifier 1b in the same manner as above described.

In the modification shown in FIG. 2, a first fuse 6 is connected between the collector electrode of transistor TR_1 and source E_1 . Another fuse 6 is connected between the collector electrode of transistor TR_2 and source E_2 . The collector electrode of the first transistor is connected to the anode electrode of silicon controlled rectifier SCR_1 through a diode D_5 having a polarity as shown in the drawing. Likewise the collector electrode of the second transistor TR_2 is connected to the cathode electrode of silicon controlled rectifier SCR_2 through diode D_6 . The connection of other elements is identical to that shown in FIG. 1.

Upon occurrence of a DC voltage of positive polarity at output terminal 2, a unidirectional short circuiting circuit is established between source E_1 and the ground via one of the fuses 6, diode 5 and silicon controlled rectifier SCR_1 . On the other hand, where a DC voltage of the negative polarity appears at the output terminal a second unidirectional short circuiting circuit is established between source E_2 and the ground via the other fuse, silicon controlled rectifier SCR_2 , diode D_6 and the other fuse 6.

Where there is another amplifier 1b, the collector electrode of transistor TR_1 of this amplifier is connected to the anode electrode of silicon controlled rectifier SCR_1 via a diode D_5' while the collector electrode of transistor TR of the second amplifier 1b is connected to the cathode electrode of silicon controlled rectifier SCR_2 via diode D_6' . Furthermore, the output terminal of the second amplifier 1b is connected to the juncture between resistor R_1 and capacitor C_1 via a resistor R_1' , as shown by dotted lines.

In the modified embodiment shown in FIG. 3, a normally closed contact 8 of a relay RY is connected between output terminal 2 and loudspeaker 3. A series circuit-including an NPN type transistor Q_1 and relay RY connected to the collector electrode of transistor Q_1 is energized by a source E_3 through a switch S, the negative pole of source E_3 being connected to the emitter electrode of transistor Q_1 . Although not shown in the drawing, switch S is interlocked with a source switch for amplifier 1a. A capacitor C_4 is connected across the base and emitter electrodes of transistor Q_1 , and a resistor R_9 is connected between the base electrode of transistor Q_1 and the juncture between relay RY and switch S. A bridge rectifier circuit 9 is provided comprising a first branch including a diode D_7 and a series resistor R_1 , and a second branch including a diode D_7' and a series resistor R_{11}' . One input terminal 10 of the rectifier circuit 9 is connected to output terminal 2 via a resistor R_{12} whereas the other output terminal 10' is grounded. One output terminal 12 is connected to the base electrode of transistor Q_1 while the other output terminal 12' to the emitter electrode of transistor Q_1 . A capacitor C_5 for bypassing the audio signals is connected between input terminal 10 and the ground.

In operation, when the source switch, not shown, of amplifier 1a is closed, switch S is also closed to charge

capacitor C_4 . When the terminal voltage of capacitor C_4 reaches a predetermined value, transistor Q_1 becomes conductive to energize relay RY . Then contact 8 is closed to connect loudspeaker 3 to output terminal 2 of the amplifier. It is possible to prevent loudspeaker 3 from generating uncomfortable noise at the time of closing the source switch by the suitable selection of the time constant of a series circuit comprising resistor R_9 and capacitor C_4 .

As contact 8 is maintained closed, a positive DC voltage, appearing at the output of the amplifier is impressed across the input terminals 10 and 10' of rectifier circuit to decrease the voltage across capacitor C_4 by the output voltage of the opposite polarity produced by the rectifier. When the voltage across capacitor C_4 is decreased to a predetermined level, transistor Q_1 is turned OFF thus deenergizing relay RY to open contact 8. In this manner, the loudspeaker 3 and output transistors TR_1 and TR_2 are protected from burning out.

When a negative DC voltage appears at output terminal 2, a voltage of the opposite polarity is impressed across the input terminals 10 and 10' of rectifier circuit 9. However, as the rectifier circuit produces unidirectional outputs, contact 8 is opened in the same manner as above described.

The above described protection for the output transistor and the loudspeaker continues as long as the abnormal voltage persists and upon disappearance of the abnormal voltage the contact 8 is reclosed after a predetermined time.

If diodes are substituted for resistors R_{11} and R_{11}' of the bridge rectifier circuit 9 more satisfactory results could be obtained. Furthermore, transistor Q_1 may be replaced by an unijunction transistor. To apply the modified embodiment shown in FIG. 3 for a stereo device, the output terminal of another amplifier, not shown, is connected to input terminal 10 of bridge rectifier 9 via a resistor (not shown) similar to resistor R_{12} .

The object of this invention can also be accomplished by connecting a normally closed contact 15 of relay RY between the output terminal 2 of amplifier 1a and loudspeaker 3, as shown in FIG. 4. In this modified embodiment, output terminal 2 is connected to one input terminal 10 of bridge rectifier circuit 9 via resistor R_{12} . A capacitor C_5 for bypassing the audio signal is also connected to input terminal 10. The output terminals 12 and 12' are connected across a capacitor C_4 , and the other input terminal 10' of the bridge rectifier circuit 9 is grounded in the same manner as in FIG. 3. However, as the polarities of diodes D_7 and D_7' are opposite to those of the diodes shown in FIG. 3 the capacitor C_4 will be charged with the opposite polarity. The anode electrode of silicon controlled rectifier SCR_3 is connected to the positive pole of source E_3 through relay RY and switch S interlocked with the source switch, not shown, of the amplifier 1a while the cathode electrode is connected to the negative pole of source E_3 . The gate electrode and the cathode electrode of the silicon controlled rectifier SCR_3 is connected in parallel with capacitor C_4 .

Under normal conditions, since the terminal voltage of capacitor C_4 is zero the relay RY will not be energized even if contact S were closed whereby contact 15

is held closed. When a positive or negative DC voltage appears at output terminal 2, capacitor C_4 will be charged with a polarity shown in FIG. 4. When the terminal voltage of capacitor C_4 reaches a predetermined value silicon controlled rectifier SCR_3 becomes conductive to energize relay RY thus opening contact 15.

With this embodiment too, it is also possible to protect a plurality of loudspeakers by providing another normally closed contact operated by relay RY and another resistor which is identical to resistor R_{12} and connected to the output terminal of another amplifier.

The object of this invention can also be accomplished by connecting normally closed contacts, not shown, of relay RY respectively in series with the collector electrodes of transistors TR_1 and TR_2 .

FIG. 5 shows a connection diagram of a modified embodiment of this invention as applied to a four channel stereo device. More particularly, two terminals of the opposite polarity of two sources (such as E_1 and E_2 shown in FIG. 1) of each one of four amplifiers 1a through 1d are grounded and the output terminals of these amplifiers are connected to one terminal of resistors R_{13a} through R_{13d} , respectively. Each one of the amplifiers is provided with a signal input terminal 4. Output terminals 2a to 2d of respective amplifiers are connected to respective loudspeakers respectively through normally closed contacts 15a to 15d of a relay RY . Further, the output terminals are grounded through resistors R_{14a} through R_{14d} respectively. A pair of bridge rectifier circuits 9a and 9b are provided including diodes D_8 through D_{11} and diodes D_{10} through D_{13} , respectively. A capacitor C_7 is connected across the input terminals 16 and 17 of rectifier circuit 9a. Input terminal 16 is connected to the opposite terminals of resistors R_{13a} and R_{13b} whereas the input terminal 17 is grounded. One input terminal 18 of rectifier circuit 9b is connected to the other terminals of resistors R_{13c} and R_{13d} and a capacitor C_{10} is connected between two input terminals 17 and 18 of the rectifier circuit 9b. A positive output terminal 19 and a negative output terminal 19' which are common to both rectifier circuits are connected across capacitor C_8 . Furthermore, output terminal 19' is grounded through a capacitor C_9 . Resistors R_{13a} and R_{13b} and capacitor C_7 cooperate each other to act as a low frequency blocking filter for the outputs from amplifiers 1a and 1b so that when a DC voltage of one polarity or an undesirable low frequency signal appears on the output terminals of these amplifiers. An input signal is applied across input terminals 16 and 17 of the rectifier circuit 9a. Likewise resistors R_{13c} and R_{13d} and capacitor C_{10} constitute a low frequency blocking filter for the outputs from amplifiers 1c and 1d so as to apply an input signal across input terminals 17 and 18 of the rectifier circuit 9b upon occurrence of a DC voltage of one polarity or an undesirable low frequency signal at the output terminals of these amplifiers.

Relay RY is energized from an AC source 20 via a rectifier including a diode D_{15} and a smoothing capacitor C_{11} . The collector electrode of an NPN type transistor Q_3 is connected to the cathode electrode of diode D_{15} through a resistor R_{15} while the emitter electrode of the transistor is connected to the negative output terminal 19' of rectifier circuits 9a and 9b via a resistor R_{16} . The base electrode of transistor Q_3 is con-

nected to the positive terminal 19 of the rectifier circuits. The base electrode is also connected to the negative terminal 19' through a biasing capacitor C₈. The collector electrode of another NPN type transistor Q₄ is connected to the cathode electrode of diode D₁₅ through a diode D₁₆ while the emitter electrode of transistor Q₄ is connected to the emitter electrode of transistor Q₃. The base electrode of transistor Q₄ is connected to the collector electrode of transistor Q₃ and to the negative output terminal 19' via a biasing capacitor C₁₂. Transistors Q₃ and Q₄ constitute a Schmidt circuit. The relay RY is connected across the anode and cathode electrodes of diode D₁₆.

Since transistor Q₄ is maintained normally in the conductive state by the bias voltage provided by capacitor C₁₂, relay RY is energized to maintain its contacts 15a through 15d in the closed condition. When a positive DC voltage appears at the output terminal of one of the amplifiers 1a through 1d, for example 1a, a current flows through a circuit that can be traced from output terminal 2a to the ground through resistor R_{13a}, diode D₈, transistor Q₃, resistor R₁₆, diode D₁₁ and grounded output terminal 21. On the contrary, where a negative DC voltage appears, a current flows from grounded terminal 21 through diode D₁₀, transistor Q₃, resistor R₁₆, diode D₉ and resistor R_{13a} to the output terminal 2a. When the voltage across capacitor C₈ reaches a predetermined value transistor Q₃ becomes conductive to turn OFF transistor Q₄. Accordingly, relay RY is deenergized to open contacts 15a through 15d.

FIG. 6 shows a connection diagram of a protective device for loudspeakers of a two channel stereo device having two amplifiers corresponding to amplifiers 1a and 1c of the circuit shown in FIG. 5. The elements corresponding to those shown in FIG. 5 are represented by the same reference characters. Terminals 22 and 23 represent the output terminals of the amplifiers and across terminals 19 and 19' is connected the relay control circuit shown.

The circuit shown in FIG. 7 shows a protective circuit for loudspeakers of a three channel stereo device including three amplifiers shown in FIG. 5, for example amplifiers 1a, 1b and 1c. Terminals 24, 25 and 26 are connected to the output terminals of these amplifiers, respectively, and across output terminals 19 and 19' is connected the relay control circuit shown in FIG. 5 including relay RY. Since output terminals of respective amplifiers are connected to independent low frequency blocking filters, respectively including resistor R_{13a} and capacitor C₁₃, resistor R_{13c} and capacitor C₁₄ and resistor R_{13b} and capacitor C₁₅, there are provided three bridge rectifier circuits 9c, 9d and 9e including eight diodes, some of them being used in common for two rectifying circuits. Like FIG. 5, a relay control circuit including a relay is connected across terminals 19 and 19'. The operation of the circuit shown in FIG. 7 is similar to that of the circuit shown in FIG. 5.

What is claimed is:

1. In an audio amplifier comprising first and second transistors with their emitter-collector circuits connected in series to provide an output terminal, first and second sources respectively connected in series with said first and second transistors, and a loudspeaker

connected directly to said output terminal, a protective device for said loudspeaker comprising:

a relay contact connected in series with a first closed circuit including said first transistor, said first source and said loudspeaker; and in series with a second closed circuit including said second transistor, said second source and said loudspeaker; and

a control circuit which comprises a bridge rectifier circuit having an input terminal connected to said output terminal; and a relay circuit connected to the output terminal of said bridge rectifier circuit; said bridge circuit converting a positive or negative direct current voltage appearing at said output terminal into a direct current voltage of a given polarity; and said relay circuit opening said relay contact when said rectified direct current voltage exceeds a predetermined level.

2. Apparatus according to claim 1 wherein said relay circuit comprises a switch interlocked with the power switch of said amplifier; a capacitor connected to be charged to a predetermined voltage in a predetermined time after said switch has been closed; means for closing said relay contact in opened position when the voltage across said capacitor reaches a predetermined value; and means for decreasing the voltage across said capacitor in accordance with the output of said bridge rectifier circuit for opening said relay contact in closed position.

3. Apparatus according to claim 1 wherein said first and second sources are of opposite polarity.

4. In an audio amplifier arrangement comprising a plurality of amplifiers, each of said amplifiers including first and second transistors with their emitter-collector circuits connected in series to provide an output terminal, first and second sources respectively connected in series with said first and second transistors, and a loudspeaker connected directly to said output terminal, a protective device for said loudspeakers comprising:

a circuit interrupting element comprising a plurality of relay contacts respectively connected in series with a first closed circuit which includes said first transistor of each of said amplifiers, said first source and said loudspeaker; and in series with a second closed circuit of each of said amplifiers including said second transistor, said second source and said loudspeaker; and

a control circuit coupled in common to the output terminals of each of said amplifiers, said control circuit comprising a plurality of bridge rectifier circuits, predetermined branches of said bridge rectifier circuits being coupled in common for two adjacent rectifier circuits, a plurality of low frequency blocking circuits for applying to the input terminals of said rectifier circuits a DC voltage and an output of less than a predetermined frequency which appears at the output terminals of said amplifiers, and a relay circuit which opens the relay contacts when the out-puts from said rectifier circuit exceeds a predetermined value.

5. Apparatus according to claim 4 wherein said first and second sources are of opposite polarity.
